UNITED STATES PATENT OFFICE.

EMIL CRISAND, OF NEW HAVEN, CONNECTICUT, ASSIGNOR TO HENRY ST. JOHN, OF SAME PLACE.

DESIGN FOR EMBROIDERY-PATTERNS.

Specification forming part of Design No. 7,895, dated November 24, 1874; application filed November 7, 1874.
[Term of Patent 3½ years.]

CASE G.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto forming the base of this design is "Love One Another." The form of the let-

ters composing the several words is clearly shown in the accompanying illustration, the capitals being the principal features in this part of the design.

The ornamentation in this design consists of a vine or tracing of scroll-work, springing from the beginning of the motto and running through, as shown in the accompanying illustration.

I claim—

The design for embroidery-patterns herein described, consisting of the motto "Love One Another," in form and ornamentation as shown in the accompanying illustration.

EMIL CRISAND.
